W. B. Ford

Attorney

UNITED STATES PATENT OFFICE.

VIRGIL H. MATHES, OF INDIANAPOLIS, INDIANA.

TIMER.

Application filed November 13, 1925. Serial No. 68,892.

My said invention relates to improvements in timers or distributors for ignition systems of internal combustion engines and it is an object of the invention to provide a 5 device of this character in which springs are practically eliminated and which is simpler in construction, more positive in action, and which can be produced at a very slight cost.

10 Another object of the invention is to provide an improved distributor head having practically no metal parts therein other than those which form the contacts thereby precluding accidental short circuiting.

15 Referring to the accompanying drawings which are made a part hereof and on which similar reference characters indicate similar parts,

Figure 1 is a side elevation of a front 20 end of an internal combustion engine showing my device attached thereto,

Figure 2, a front elevation,

Figure 3, an enlarged longitudinal section view,

25 Figure 4, a top plan view with the cover and some of the parts removed, and

Figure 5, a similar view with additional parts removed.

As shown in the drawings my invention 30 comprises a casing 10 for attachment to the cam shaft 11 of an engine of the Ford or similar type. The peripheral wall of the casing 10 is provided with a plurality of longitudinally spaced openings 12 about 35 which are mounted a plurality of sleeves 13 arranged in substantially parallel relation and substantially at right angles to the casing 10. The upper ends of the sleeves 13 are secured to a plate 14 which is fastened 40 by screws or the like to the under side of a housing 15 formed of material of good insulation properties.

The housing 15 has a slot 16 in its bottom through which extend the upper ends 45 of push rods 17 located in the sleeves 13 and adapted to reciprocate therein. Said housing is also provided with a contact 19 for each of the push rods and these contacts are located one in each of the four corners of 50 the housing at the bottom of vertically arranged grooves or recesses and are engaged by lateral extension 18 on the push rods 17. The contacts 19 are formed of flattened metallic strips and are held in place by threaded connections with bolts extending through 55 the bottom of the housing. The threaded

bolts extend through the contacts 19 and provide mountings for the terminals 20 which extend slightly above the top of the housing 15. Said terminals may be provided 60 with sockets for the reception of conductors not shown.

The lateral extensions of the push rods terminate short of the terminals 20 but are limited in their lateral movement by the 65 sides of the vertically disposed recesses or grooves. On account of this construction it will be impossible for the lateral portions on the push rods to accidentally move out of position where they will not seat upon 70 their cooperative contacts when the push rods are raised and lowered during the operation of the engine.

In order to make and break the connection at the proper intervals I provide a cam 21 75 and fasten the same to the camshaft, said cam has a flat face or depression for each push rod so that the revolution of the cam will keep the push rod raised and the extension 18 off the contact 19 for the greater portion 80 of the revolution but permit the same to be lowered and the contact to be completed.

In order to maintain the push rods and the lateral extensions at the upper ends 85 thereof in engagement with their respective contacts a plurality of rubber disks are threaded upon a core to form a rubber cylinder, one of which is positioned on each lateral extension on the upper end of the 90 push rod for holding the same against its corresponding contact. A block 23 is placed centrally across the housing for maintaining the rubber cylinders over their respective contacts.

95 A cover 24 is provided for the housing 15 and this cover is held in place by screws 25 and in turn compresses the rubber cylinders against their respective laterally extending contact elements.

100 It will be obvious to those skilled in the art that various changes may be made in my device without departing from the spirit of the invention and therefore I do not limit myself to what is shown in the drawings and described in the specification but only as indicated in the appended claims:

Having thus fully described my said invention, what I claim as new and desire to secure by Letters Patent, is:

110 1. In a timer for engines, the combination of a casing, a cam within said casing, a

- housing in spaced relation to said casing, contacts in said housing, a plurality of sleeves connecting said housing and casing, and push rods disposed in said sleeves and 5 having laterally extending upper ends overlying said contacts and adapted for engagement therewith, substantially as set forth.
2. A timer comprising a casing, a housing, sleeves connecting said casing and housing, 10 contacts within said housing, rods disposed in said sleeves said rods having their upper ends provided with lateral extensions overlying said contacts, spring means for holding said lateral extensions in engagement 15 with said contacts, and a cam in said casing for operating said push rods, substantially as set forth.
3. A timer comprising a casing, a housing, sleeves connecting said casing and housing, 20 contacts within said housing, rods disposed in said sleeves said rods having their upper ends provided with lateral extensions overlying said contacts, insulated springs
- resting on said lateral extensions, and a cover for said housing holding said insulated 25 springs against said lateral extension, substantially as set forth.
4. A timer comprising a casing, a housing, sleeves connecting said casing and housing, contacts within said housing, rods disposed in said sleeves said rods having their upper ends provided with lateral extensions 30 overlying said contacts, spring means formed of insulating material resting on said lateral extensions, and a cover for said housing holding said insulating spring means against said lateral extensions said housing having spaced recesses for maintaining the lateral extensions and their associated contacts from lateral separation, substantially as set forth.

In witness whereof, I have hereunto set my hand at Indianapolis, Indiana this 10th day of November, A. D. nineteen hundred and twenty-five.

VIRGIL H. MATHES.
